UNITED STATES PATENT OFFICE

2,375,604

GRINDING MACHINE

Clarence R. Williams, Brooklyn, N. Y., assignor
to Atlantic Service Company, Inc., Brooklyn,
N. Y., a corporation of New York

Application January 2, 1942, Serial No. 425,428

11 Claims.

(Cl. 51—135)

This invention relates to grinding machines of the abrasive belt type for sharpening knives and similar articles and is an improvement upon the grinding machine shown in U. S. Patent 2,222,966 issued in my name on November 26, 1940.

An object of the present invention is to provide an improved tool holding mechanism for this type of machine which is readily adapted to a variety of tools. Other objects of the invention will be apparent from the following specification and the accompanying drawings, in which:

Fig. 1 is a side elevation of the housing of the grinding mechanism with the cover removed;

Fig. 2 is a side elevation of the mechanism taken on the opposite side from Fig. 1;

Fig. 3 is a top plan view of the mechanism;

Fig. 4 is a side elevation of the tool holding mechanism by itself, without the housing;

Fig. 5 is a side elevation of the tool holding mechanism on the opposite side from Fig. 4, except adjusted for a heavier tool and

Fig. 6 is an end view from the left of Fig. 5.

This machine comprises a housing enclosing a pair of belt wheels upon which an abrasive belt is mounted and one of these wheels is driven by a motor exterior of the housing (not shown in this case) to move the belt under the tool that is being sharpened. A portion of the top of the housing is removable to expose a portion of the belt, but is locked in its operating position, and an adjustable tool holder is pivotally mounted on the housing to hold the tool in a predetermined position relative to the belt while it is being ground or sharpened.

The tool holding mechanism comprises a pair of plates, the upper edges of which are adjustable relative to the plane of the belt to determine the angular position of the tool relative to the belt and also to a pivoted guard and guide member, which partially covers the belt and which is latched in its operative position. A bail is pivotally secured to the guide member with its free end supported by said tool holding plates and is arranged to provide a single point of support for the side of the tool, the sharpened edge of which is supported on said belt. The guard member and the bail may be turned back clear of the abrasive belt when the whole surface of the belt is to be used for other grinding purposes.

In the drawings, 11 is the mechanism housing in which is the driving pulley 12, mounted on the shaft 13, and a following pulley 14 mounted on the stud 15, which is journaled in a box on the housing. Between the pulleys 12 and 14 the abrasive belt 16 is mounted and passes over the

aligned spring tables 17 and 18 which are secured to the inner frame 19, that in turn is fixed to the housing 11. The shaft 13 is driven by a suitable motor arranged to maintain the belt taut as shown in the above mentioned patent.

A pair of adjustable supporting plates 21 and 22, pivoted at 23 to the frame 19 and tied together by a rod 24, are located one on each side of the pulley 14 and within the housing. An arcuate arm 25 is connected to plate 22 and extends outside the housing where it is provided with a slot 26 by means of which the arm is held in adjusted position by nut 27. A finger grip 28 on this arm passes over the graduated scale 29 on the housing to indicate the angular position of the upper edges of plates 21 and 22 relative to the plane of the grinding surface of the belt. The slot 26 will permit this adjustment to an angle of thirty-five degrees, but any desired limits may be arranged. A rest and dust guard 30 is provided at the front end of the housing 11, the height of which is adjustable, the guard being held by the wing nut 31.

A sleeve 51, developed from the top of the housing 11, supports the pivot 52 of the inclined guard and guide plate 53, the free edge of which terminates in the turned up flange 54. The guard plate overlies the belt and is provided with dependent side wings 55 which pass between the opposite sides of the belt and the housing. One of these side wings is provided with a horizontal slot 56 to receive the locking lever 57 that is pivoted at 58 to the frame 19. When the guide plate 53 is brought into the operating or grinding position as indicated in Figs. 2 and 5, the lever 57 is moved forwardly into the slot 56 and rigidly secures the plate 53 with the lower edge of flange 54 spaced from the belt 16. It is against this lower edge that the side of the tool or knife engages during grinding.

A bail 60 is provided with the turned-in ends 61 and 62 which enter apertures in the wings 55 of the guide plate 53, forming a pivoted connection therewith. The bail is somewhat wider than the frame so that its crossbar can engage the upper edges of the supporting plates 21 and 22 in one position of the bail. The crossbar of the bail is preferably bent upwards at the center, as indicated at 63, Fig. 6, so that when the bail is supported by the plates 21 and 22 the bend 63 provides a single point support for the side of the tool, which point is located centrally of the abrasive belt. Usually, the bail is used only for the heavier tools, such as butchers' cleavers, and

otherwise it is swung back upon the guide plate 53, as seen in Figs. 1 to 4.

In operation the supporting plates 21 and 22 may be adjusted to whatever height is best for the particular knife or tool, such as indicated in Fig. 4 for the tool b. This adjustment varies from the position where the upper edges of the supporting plates are substantially in the same plane as the top of the belt 16, as seen in Fig. 2, to a somewhat pronounced angle to the plane of the belt, limited only by the length of the slot 26 in the arm 25. The side of the knife or tool rests on the upper edges of these supporting plates 21 and 22 as it is being sharpened, unless the bail 60 has been lowered as shown in Fig. 5, in which case the cleaver or other tool rests on the point 63 thereof, as explained above. It will be understood, of course, that the supporting plates are similarly adjustable when the bail is in the position shown in Fig. 5.

When the guide member 53 is latched in position as indicated in dotted outline in Fig. 4 and in full lines in Fig. 5, the flange 54 forms an abutment for the upper side or face of the tool, while the lower side or face is supported by the adjustable plates 21 and 22 and the belt. In this position the edge of the knife projects under the flange 54 into space which is unobstructed except for the belt 16 that passes therethrough, so that the cutting edge of the tool may be sharpened to "infinity" for both thin and thick tools. The tool may be drawn back and forth across the belt as indicated at a, Fig. 3, the tool being guided by the lower edge of flange 54, and if the tool is a common table knife with a polished surface the plates 21 and 22 may be so adjusted as to protect the polished surface from the abrasive belt while the edge is being ground.

The wedge-shaped tool d, Figs. 5 and 6, may be in the form of a cleaver and a three-point support may be preferable for a tool of this type, comprising a single support on the center line of the belt and the broader support by the belt 16.

When the belt is to be replaced on the pulleys the guard member 53 is turned back and the side plates 21 and 22 are lowered, making the belt readily accessible from the side of the mechanism which is opened by removal of the cover 64.

Having thus described my invention, I claim:

1. A grinding machine comprising a housing with a pair of belt wheels, one of which is driven to move the belt, an abrasive belt mounted on said wheels, a combined guard and tool guide for said belt comprising a plate pivoted to said housing and overlying said belt, means for latching said guard in the operative position, means on said guard engaging the tool to hold the edge of the tool in engagement with the belt when the guard is in latched position, and separate adjustable means for supporting the tool in operative position.

2. A grinding machine comprising a housing with a pair of belt wheels, one of which is driven to move the belt, an abrasive belt mounted on said wheels, a combined guard and tool guide for said belt comprising a plate pivoted to said housing and overlying said belt, a slot in said guard, a lever pivoted to the housing and arranged to engage said slot to lock said guard in the operative position, means on said guard engaging the tool to hold the edge of the tool in engagement with the belt when the guard is in latched position, and separate adjustable means for supporting the tool in operative position.

3. A grinding machine comprising a housing

with a pair of belt wheels, one of which is driven to move the belt, an abrasive belt mounted on said wheels, a tool guide comprising a plate pivoted to said housing and overlying said belt and having turned down sides with a slot in one of said sides, a lever pivoted to said housing engaging said slot to position, and lock said plate in the operative position and the forward end of said plate being bent upwards to reinforce the edge of said plate where it engages the tool to hold the edge of the tool in engagement with the belt.

4. A grinding machine comprising a housing with a pair of belt wheels, one of which is driven to move the belt, an abrasive belt mounted on said wheels, a tool rest comprising a bail pivoted to said housing, said bail when in the operative position having a single raised portion over the belt to engage the tool and form a support about which the tool may pivot.

5. A grinding machine comprising a housing with a pair of belt wheels, one of which is driven to move the belt, an abrasive belt mounted on said wheels, a tool rest comprising a bail pivoted to said housing, adjustable means engaging the free end of the bail to vary its angle relative to the plane of the belt, said bail when in the operative position having a single raised portion over the belt to engage the tool and form a support about which the tool may pivot.

6. A grinding machine comprising a housing with a pair of belt wheels, one of which is driven to move the belt, an abrasive belt mounted on said wheels, a tool rest and guard for said belt comprising a plate pivoted to the housing and extending over said belt, a bail pivoted to said plate, means for locking said plate in the operative position, means for adjustably supporting the free end of said bail, and means cooperating with said bail providing a three point support for the tool in the grinding position.

7. A grinding machine comprising a housing with a pair of belt wheels, one of which is driven to move the belt, an abrasive belt mounted on said wheels, a tool rest and guard for said belt comprising a plate pivoted to the housing and extending over said belt, a bail pivoted to said plate, means for locking said plate in the operative position, said plate having its edge extending at right angles to the line of movement of the belt, and said bail in the operative position having a single raised portion above the center of the belt to engage the under side of the top of the tool while the edge of the plate engages the tool to hold it in the grinding position.

8. A grinding machine comprising a housing with a pair of belt wheels, one of which is driven to move the belt, an abrasive belt mounted on said wheels, a tool rest and guard for said belt comprising a plate pivoted to the housing and extending over said belt, a bail pivoted to said plate, means for locking said plate in the operative position, a pair of adjustable plates also pivoted to said housing with their edges adjustable relative to the plane of the belt, means for adjusting the position of said last mentioned plates, the free end of said bail resting upon said plates and providing with the edge of the first mentioned plate a support and guide for the tool in the grinding position.

9. A grinding machine comprising a housing with a pair of belt wheels, one of which is driven to move the belt, an abrasive belt mounted on said wheels, a rest for the tool in the grinding position, comprising a pair of plates pivoted to

said housing with their edges adjustable relative to the plane of the belt, means for adjusting the position of said plates, and a member adjustably supported by said plates and engaging the tool above the center line of the belt to support the tool in the grinding position.

10. In a grinding machine, a housing, a pair of belt wheels mounted therein, one of which is driven to move a belt, an endless abrasive belt rotated by said wheels, a tool guide extending across the belt and fixed in spaced relation thereto, and a tool support adjustable relative to the plane of the belt without adjusting the guide, the support cooperating with said guide in its several adjusted positions so that the tool can enter 15 said space and engage the belt according to the desired angle of the particular cutting edge.

11. In a grinding machine, a housing, a pair of belt wheels mounted therein, one of which is driven to move a belt, an endless abrasive belt rotated by said wheels, a tool guide extending across the belt and fixed in spaced relation thereto, a tool support adjustable relative to the plane of the belt and cooperating with said guide so that the tool can enter said space and engage the belt according to the desired angle of the particular cutting edge, and means movable to position to provide a single point support on the side of the tool as it is being sharpened, while the end of the tool is supported on the belt and guided by the tool guide.

CLARENCE R. WILLIAMS.
